(57) **CLAIM**

What is claimed is the ornamental design for a valve body, as shown and described.

DESCRIPTION

FIG. 1 is an upper perspective view of a valve body showing my new design.

FIG. 2 is a lower perspective view of the valve body;

FIG. 3 is a side view of the valve body;

FIG. 4 is another perspective view of the valve body; and FIG. 5 is a cross-sectional view of the valve body as shown in FIG. 6, taken through line 5-5; and,

FIG. 6 is a plan view of the valve body.
